US0D1082341S

(12) **United States Design Patent** (10) Patent No.: **US D1,082,341 S**
(45) Date of Patent: ** Jul. 8, 2025

(54) **PICTURE FRAME**

(71) Applicant: **Zhennan Liu**, Hunan (CN)

(72) Inventor: **Zhennan Liu**, Hunan (CN)

(**) Term: **15 Years**

(21) Appl. No.: **29/981,153**

(22) Filed: **Dec. 30, 2024**

(51) LOC (15) Cl. **14-02**

(52) U.S. Cl.

USPC **D6/308**; D6/310; D14/374

(58) **Field of Classification Search**

USPC D6/300-314; D14/371, 374

CPC ... A47G 1/00; A47G 1/06; A47G 1/12; A47G 1/16

(57) **CLAIM**

The ornamental design for a picture frame, as shown and described.

DESCRIPTION

FIG. 1 is a front, right and top perspective view of a picture frame showing my new design;

FIG. 2 is a rear, left and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the figures depict portions of the picture frame that form no part of the claimed design.

1 Claim, 8 Drawing Sheets
